UNITED STATES PATENT OFFICE.

CHARLES H. ALLEN AND GLENN S. SOSEMAN, OF CHICAGO, ILLINOIS, ASSIGNEES TO
THE ALLENLITE COMPANY, OF CHICAGO, ILLINOIS, A CORPORATION OF ILLINOIS.

HEADLIGHT.

Application filed November 15, 1924, Serial No. 750,048. Renewed May 9, 1927.

This invention relates to headlights for a front surface of somewhat less radius automotive vehicles and the like wherein a non-glaring illumination is required with a combination of near and far lighting effects.

5 This invention is an improvement of that shown in Charles H. Allen's application for U. S. Letters Patent, Serial No. 655,160, filed August 2nd, 1923.

It is an important object of this invention 10 to provide the combination of diffused rays of light for near illumination and concentrated nearly parallel rays of light for distant illumination with the entire absence of objectionable glare or stray rays of light in 15 the eyes of approaching drivers or pedestrians.

Other and further important objects of this invention will be apparent from the disclosures in the drawings and accompanying 20 specification.

This invention (in a preferred form) is illustrated in the drawings and hereinafter more fully described.

On the drawings:

25 Figure 1 is a vertical section of a reflector and lamp mounting embodying the features of this invention.

Figure 2 is a front elevation thereof.

As shown on the drawings:

30 The reference numeral 5 refers to a cylindrical shell supporting a lamp bracket 6 with a light source 7 located well below the center of the shell. As shown, the light source 7 comprises an electric bulb facing rearwardly to obtain the full reflecting power of the lamp with the minimum amount of direct projected rays of light. Preferably integral with the cylindrical shell is a spherical segment forming a back 35 or closure 8 whose center 9 falls on a horizontal line through the light source. The low position of the light source gives the chord of the spherical segment a forward inclination. A polished reflector 10 is arranged in the upper half of the spherical back, and due to the inclination of the back and the position of the light source inside the center of the reflector, the light rays reflected thereby will be downwardly directed 45 and widely dispersed for the purpose of illuminating the immediate surroundings 50 and below the level of the headlight.

A reflector 11 of the well known Mangin type having a silvered rear surface of a 55 curvature corresponding to the shell 8 has

thereby forming a concentrating reflector adapted to project nearly parallel horizontal rays of light to illuminate distant objects. The Mangin reflector extends upwards only 60 to the horizontal line through the light source, leaving a blank or nonreflecting surface 12 on the rear wall or shell 8 extending from the edge of the lower reflector to the edge of the upper reflector, in the zone that 65 in an ordinary headlight produces most of the objectionable reflected rays of light, that would rise to the height of an approaching driver's or pedestrian's eyes, thereby temporarily blinding him.

70 We claim as our invention:

1. In a light projector, a casing, a light source facing toward said casing, a spherical reflector segment in the upper portion of said casing with its lower boundary edge 75 above the horizontal plane passing through said light source, and a Mangin reflector segment in the lower portion of said casing and having its upper boundary edge in line horizontally with said light source, no portion of either segment extending ahead of the light source, the position of the light source with respect to the foci and axes of said segments being such that the rays from the upper segment are projected downward 80 while the rays from the Mangin segment are projected horizontally.

2. In a light projector, a casing embodying a spherical back, a light source mounted along the horizontal axis of said back and facing toward it, a spherical reflector segment in the upper portion of said casing and fitting said spherical back with its lower boundary edge above the horizontal plane passing through said light source, and a 90 Mangin reflector segment in the lower portion of said casing with its rear face fitting said back and having its upper boundary edge in line horizontally with said light source, no portion of either segment extending ahead of the light source, the position of the light source with respect to the foci and axes of said segments being such that the rays from the upper segment are projected 95 downward while the rays from the Mangin segment are projected horizontally.

3. In a light projector, a casing embodying a spherical back, a light source mounted along the horizontal axis of said back and facing toward it, a spherical reflector seg- 100 105 110

ment in the upper portion of said casing with its lower boundary edge above the horizontal plane passing through said light source, and a Mangin reflector segment 5 mounted in the lower portion of said casing and having its upper boundary edge in line horizontally with said light source, the front edge of the upper reflector segment being in a plane at an angle to the transverse vertical 10 plane passing through the light source, the front edge of the Mangin reflector segment being substantially parallel with said plane, and the position of the light source with respect to said reflector segments being such 15 that the rays from the upper segment are projected downward while the rays from the Mangin segment are projected horizontally.

4. In a light projector, a casing comprising a cylindrical shell disposed horizontally 20 and a spherical segmental back united to said shell at an upward and forward angle to the vertical, a light source supported by said shell substantially below the center of the latter and in the horizontal line of the

axis of said spherical back, a spherical reflector segment in the upper portion of said casing with its lower boundary edge above and at an angle to the horizontal plane passing through said light source, and a Mangin reflector segment mounted in the lower portion of said casing and having its upper boundary edge in line horizontally with said light source, the front edge of the upper reflector segment being in a plane at an angle to the transverse vertical plane passing 30 through the light source, the front edge of the Mangin reflector segment being substantially parallel with said plane, and the position of the light source with respect to said reflector segments being such that the rays 35 from the upper segment are projected downward while the rays from the Mangin segment are projected horizontally.

In testimony whereof, we have hereunto subscribed our names.

CHARLES H. ALLEN.
GLENN S. SOSEMAN.
